UNITED STATES PATENT OFFICE.

GEORGE MAYER, OF BRONX, NEW YORK.

ATTACHMENT FOR MOVING-PICTURE PROJECTORS.

Application filed April 11, 1927. Serial No. 182,722.

This invention relates to moving picture projectors and has for its principal object to provide a new and improved attachment adapted to be secured to a well known type 5 of hand operated projector for converting it into a power driven machine.

The above and other objects of my invention will appear more fully from the following more detailed description and by reference to the accompanying drawings forming a part hereof and wherein Fig. 1 is a front elevation of a projecting machine showing my attachment secured thereto; Fig. 2 is a side elevation of the structure shown in Fig. 1 and Fig. 3 is a detail perspective view of the attachment bracket.

In Figs. 1 and 2 of the drawings I have shown a moving picture projector 10 of the type with which my improved attachment is intended for use. Machines of this type are provided on each side thereof with a gear train, the construction and operation of which need not, for the purposes of the present application, be described in detail as such 20 form no part of the present invention. It will be sufficient to state that the gear train shown at the right hand side of Fig. 1 and of which the gear 11 forms a part drives the film sprockets 12, 13, while the gear train shown at the left of said figure and of which the gear 14 forms a part drives a fly wheel 15 and other parts of the projector. Both gear trains are driven in unison through the medium of a transverse shaft 16 to which are 25 secured the gear 14 above mentioned and the gear 17, the latter being in mesh with the gear 11 and driving the right hand gear train. Also secured to said shaft 16 is a skew gear 18 which meshes with and drives 30 a co-operating skew gear secured to a shutter shaft 19 which extends at a right angle to the shaft 16.

The use of an attachment for driving by power a projector of the type shown is not 45 broadly new as such attachments have heretofore been employed. The attachments heretofore used however have been provided with gearing which meshes with and drives gear 11 of the right hand gear train. In 50 order that the proper driving speed of the machine may be readily secured it has been the practice to so design the gears of the attachment that the belt pulley of the attachment will perform one complete rotation for 55 each complete rotation of the shutter shaft 19. For securing this desired speed ratio,

it has been necessary with the attachments as heretofore constructed to provide them with a reduction gear train consisting of three gears. Owing to the provision of these 60 extra gears and also due to the fact that the attachment driving pinion meshed with the gear 11, a relatively large gear which drives the small gear 17, the prior attachments have many objectionable features, such as requiring the use of too much power, and causing the gear 11 to be rendered useless by wear in a comparatively short time. In addition, another objectionable feature of such attachments is that as they are clamped upon 65 one side only of the bottom flange of the frame casting of the projector, the casting 70 is frequently cracked or broken by the concentration of the strains in a relatively small part thereof.

In accordance with my invention, instead of having the attachment bracket secured to one side only of the machine frame and having the driving pinion of the attachment in mesh with the right hand gear train, I employ a bracket having a pair of bearing standards 18, 19, one at each side of the bracket, a pair of wings 20, 21 extending rearwardly from said standards, and a connecting web 22 joining said standards at the 75 front bottom part thereof. At their upper ends the standards 18, 19 are provided with suitable bearings for a jack shaft 23, one end of which projects outwardly beyond the standard 19 and has secured thereto a 80 grooved pulley 24, about which is adapted to be trained, a belt, driven from any suitable source of power, such, for example, as by a small electric motor, (not shown). To the other end of the jack shaft 23 is secured a 85 driving pinion 25 located inside the standard 18 and in mesh with the gear 14. The pinion 25 and a collar 26, also secured to said jack shaft, co-operate with the standards 18, 19, respectively, to prevent longitudinal 90 movement of said shaft.

For securing the bracket to the machine frame, each of the wings 20, 21 is provided with a slot or aperture through which may pass the bolts 27 which serve to fasten the 95 machine to a table or other support. The bracket is also provided at one side thereof with a depending lug 28, having slots 29, through which the bolts or screws 30 are adapted to pass.

By constructing the attachment as above set forth, I am enabled to impart the driv-

ing power through the medium of a single pinion 25 to the gear 14 and as this gear is not only of smaller diameter than the gear 11 and is also secured to the same shaft as the gear 17 which drives the right hand gear train, the amount of power required for driving the machine is considerably less than required for the old attachment. The power consumption is also further decreased by the substitution, for the three member gear train of the old attachment, of a single driving pinion which meshes directly with a gear of the machine. Furthermore as the gear 14 is much smaller than the gear 11, replacement cost of the gear 14 is less.

In addition as the bracket is clamped to both sides of the machine frame breakage of the latter is not only overcome but the attachment is more rigidly and more securely held in position.

A further objectionable feature of the old attachment which the present invention overcomes is that with the former it was very difficult, because of the limited space between the gear 11 and the bottom flange of the machine frame, in which space the attachment was mounted, to clean the parts thereof, while with my device ample clearance is provided between all the gears of the machine and the bracket to enable the latter to be easily cleaned.

Having thus described my invention, I claim as new and desire to secure by Letters Patent of the United States:

1. An attachment for converting a hand operated type of motion picture projector to a power driven machine, comprising a

bracket having a pair of upwardly extending bearing standards, wings extending laterally from the base of said standards, and a web joining said standards and holding them in spaced relationship, a jack shaft rotatably mounted in said bearings, and a driving pinion and a pulley mounted on said jack shaft.

2. An attachment for converting a hand operated type of motion picture projector to a power driven machine, comprising a bracket having a pair of upwardly extending bearing standards, a jack shaft mounted in said standards, and a single pinion and a belt pulley mounted on said jack shaft, said pinion meshing directly with a gear of said projector.

3. An attachment for converting a hand operated type of motion picture projector to a power driven machine, comprising a bracket having a pair of upwardly extending bearing standards, wings extending laterally from said standards and adapted to straddle the frame of said projector, and to be clamped to the base thereof, a web joining said standards, and a lug extending downwardly from said bracket and being provided with apertures through which bolts are adapted to be passed and screwed into said base, a jack shaft rotatably mounted in said standards, a pinion secured to said jack shaft and in mesh with a gear of said machine, and a belt pulley mounted on said jack shaft.

In testimony whereof I have hereunto set my hand.

GEORGE MAYER.
